(57) **CLAIM**

The ornamental design for a multimode surgical console, as shown and described.

DESCRIPTION

FIG. 1 is a top, front right perspective view of a multimode surgical console showing our new design;

FIG. 2 is a top, front left perspective view of the multimode surgical console showing the new design;

FIG. 3 is a bottom, front right perspective view of the multimode surgical console of FIG. 1;

FIG. 4 is a bottom, front left perspective view of the multimode surgical console showing the new design;

FIG. 5 is a top, rear right perspective view of the multimode surgical console showing the new design;

FIG. 6 is a top, rear left perspective view of the multimode surgical console showing the new design;

FIG. 7 is a bottom, rear right perspective view of the multimode surgical console showing the new design;

FIG. 8 is a bottom, rear left perspective view of the multimode surgical console showing the new design;

FIG. 9 is a left side elevational view of the multimode surgical console showing the new design;

FIG. 10 is a right side elevational view of the multimode surgical console showing the new design;

FIG. 11 is a top plan view of the multimode surgical console showing the new design;

FIG. 12 is a bottom plan view of multimode surgical console showing the new design;

FIG. 13 is a front elevational view of the multimode surgical console showing the new design; and,

FIG. 14 is a rear elevational view of the multimode surgical console showing the new design.

In the drawings, the broken lines show portions of the multimode surgical console that form no part of the claimed design.
